UNITED STATES PATENT OFFICE.

HANS J. BENTSON, OF WINTHROP HARBOR, ILLINOIS, ASSIGNOR TO FREDERICK C. AUSTIN, OF CHICAGO, ILLINOIS.

SELF-SHIFTING TRACK.

1,421,387.

Specification of Letters Patent. Patented July 4, 1922.

Application filed May 31, 1919. Serial No. 300,820.

To all whom it may concern:

Be it known that I, HANS J. BENTSON, a citizen of the United States of America, and a resident of Winthrop Harbor, Illinois, have invented a certain new and useful Improvement in Self-Shifting Tracks, of which the following is a specification.

This invention relates to means for supporting heavy machines, such as excavators, on the ground, so that the machine may be moved forward from time to time, and relates more particularly to means of this kind involving tracks upon which the wheels of the machine travel, and which are shifted ahead periodically, whereby the wheels will always have a smooth track upon which to travel.

Generally stated, the object of the invention is to provide a novel and improved construction and arrangement whereby the tracks are automatically shifted forward from time to time, as the machine travels along, so that no special attention is necessary for these tracks, and no control there-
20 of by the attendant, each track being automatically shifted forward as soon as the weight is removed therefrom and as soon as the weight is imposed on the other track, thus obviating the necessity of employing any special means for shifting the tracks when it is desired to move the machine forward.

It is also an object to provide certain details and features of construction and combinations tending to increase the general efficiency and the desirability of a shifting track arrangement of this particular character.

To these and other useful ends the invention consists in matters hereinafter set forth and claimed, and shown in the accompanying drawings in which—

Fig. 1 is a side elevation of the body of an excavator or other heavy machine, showing the same equipped with an automatic shifting track arrangement embodying the principles of the invention.

Fig. 2 is a longitudinal section of said machine, on a line extending through one of the tracks.

Fig. 3 is a plan of the structure shown in Fig. 1.

Fig. 4 is a horizontal section on line 4—4 in Fig. 1.

Fig. 5 is a similar view showing the tracks in a different position—that is to say, showing one track shifted forward.

Fig. 6 is a detail section on line 6—6 in Fig. 2.

Fig. 7 is a perspective of one of the pairs of segmental or half-round wheels which travel on the tracks.

As thus illustrated, the body 1 of the excavator or other heavy machine, may be of any suitable form or character, and in the drawings only one side of this body is shown, it being understood that the other side would be equipped with a shifting track arrangement of similar character. The body is provided with axles 2, each 70 axle having a pair of wheels 3 and 4 fixed thereon, and each wheel being only half round, so that the weight is first supported by one wheel and then the other, as the two wheels are oppositely disposed on the 75 axle. The outer wheels 3 travel on a track 5, and the inner wheels 4 travel on a similar track 6, the two tracks being arranged parallel and provided with grooves to prevent the wheels from running off. It will 80 be seen that all of the wheels are so arranged on their axles that the wheels 3 strike the track 5 at the same time, and thus support the weight, and that the wheels 4 operate similarly on the track 6, thus 85 shifting the weight alternately from one track to the other. The axles are all connected together by sprocket chains 7, or by any suitable means, so that the relative positions of the wheels will be maintained as 90 the machine travels along. Driving power is communicated to said wheels from an engine 8, or from any other suitable source, for example, through the medium of a sprocket chain 9 extending to a sprocket 95 wheel on one of said axles.

The means for shifting the tracks is as follows: The two tracks have their ends connected together by a flexible connection 10 extending around a sheave 11, which latter is connected to the body frame through the medium of a spring 12, this arrangement being employed at both the front and the rear ends of the machine, so that the

machine can travel in either direction. As shown in Fig. 4, the weight is being imposed upon the track 5, and is being taken off of the track 6, and as soon as the wheels 5 leave the track 6, the forward motion of 10 the machine will then pull this track 6 forward in the manner shown in Fig. 5. Of course, while the weight is being shifted from one set of wheels to the other, there 15 is a time when the weight is on both tracks, momentarily at least, and during such time the two tracks are stationary. It is for this purpose, therefore, that the springs 12 are employed—that is to say, they permit the 20 forward movement of the body frame while both tracks remain stationary, but as soon as one track is released, the tension of the 25 spring which has been stretched will jerk the released track forward, and this track will then be pulled along further by the 30 continued forward movement of the body frame. In this way, each track balances the other, so to speak, and the tracks are alternately shifted forward automatically, it will 35 be seen, merely by the forward motion of the body frame. No special attention is necessary for the shifting of the tracks, and no power other than that furnished by the forward movement of the body frame itself, is necessary for the shifting of the 40 tracks. A smooth path of travel is provided for the wheels of the machine to travel upon, so that a machine of great weight may travel across soft ground or over places 45 where it would be impossible to support the machine by direct contact of the wheels thereof with the ground. The tracks, however, simply take care of themselves, as they are dependent merely upon the forward motion 50 of the entire machine for the shifting of first one track and then the other.

By reason of the sheaves 11, and the flexible connections 10 extending around each sheave, in the manner shown, it is obvious 55 that each track when released will travel forward faster than the body frame, its speed of forward movement being substantially twice that of the body frame. In effect, each track, when held stationary by the 60 weight imposed thereon, serves to pull the other track forward, and this action is adapted to continue smoothly and without interruption for any length of time, while the machine is travelling steadily forward.

55 What I claim as my invention is:—

1. The combination of a body provided with segmental wheels, tracks resting on the ground to support said wheels, means for causing forward movement of said body, so 60 that the wheels will roll along upon said tracks, said wheels being adapted to shift the load weight alternately from one track to the other, so that the tracks are alternately relieved of weight and thereby relieved, and instrumentalities dependent 65

upon the forward motion of the body and operated thereby to automatically and alternately pull the tracks directly forward along the ground.

2. A structure as specified in claim 1, said 70 instrumentalities comprising a sheave connected to the body, and a flexible connection attached to the tracks and extending around said sheave, so that either track when released will travel forward faster 75 than the body.

3. A structure as specified in claim 1, said 80 instrumentalities comprising a sheave, means including a spring for connecting the sheave to the body, and a flexible connection attached to the tracks and extending around the sheave.

4. A structure as specified in claim 1, said 85 instrumentalities being operative to shift the tracks by either the forward or the backward movement of the body.

5. A structure as specified in claim 1, said 90 instrumentalities comprising a spring to permit forward movement of the body while both tracks remain stationary on the ground, 95 and while the two tracks momentarily both support the weight of the body, and before one track is released by the shifting of the weight therefrom to the other track.

6. The combination of a body, supporting 95 wheels for said body, tracks for said wheels, said wheels being adapted to alternately shift the load weight from one track to the other, a power plant on the body to operate 100 said wheels, thereby to propel the body forward, and means whereby either track when released is shifted directly forward from its load sustaining position by the forward motion of the body, so that said source of power serves not only to propel the body forward on the tracks, but serves also by 105 the forward motion of the body to propel the tracks forward.

7. A structure as specified in claim 6, the 110 two tracks being connected to pull one against the other, so that when one is stationary, it serves in effect to pull the other track forward.

8. A structure as specified in claim 6, the 115 means for causing the forward movement of the tracks comprising a provision to cause either track when released to travel forward faster than the body.

9. The combination of a body frame, segmental wheels for said frame, tracks supported on the ground for said wheels, and direct connections between the tracks and the body frame to pull the tracks forward by the motion of the frame, said connections having one or more springs to permit one or 120 more of the tracks to remain stationary while the load weight of the forwardly moving body frame is sustained thereon. 125

10. The combination of a pair of tracks, a body frame having half-round wheels to 130

travel on said tracks, and means for automatically pulling the tracks forward, having provisions for equalizing the pull on the two tracks.

5 11. The combination of a pair of tracks, a body frame having wheels to travel on said tracks, adapted to alternately shift the load weight from one track to the other, and

connecting means extending between the body frame and the tracks for automatically pulling the tracks alternately forward, having provisions to equalize the forward pull on said tracks, so that either track must remain stationary to cause the forward movement of the other track.

HANS J. BENTSON.
